FILE

Pierce J. Murphy, Tecumseh, Nebr.

Application February 12, 1935, Serial No. 6,228

1 Claim. (Cl. 29—80)

This invention relates to files, and particularly to the formation of a handle on the file.

The object of the invention is to provide a file with an integral metallic handle formed as a part of the file, the handle being in the form of an elongated loop, thus doing away with the necessity of using wooden handles on files, or attachable and detachable handles therefor, and providing means whereby the file may be hung up.

My invention is illustrated in the accompanying drawing, wherein:—

Figure 1 is a face view of a file having a handle constructed in accordance with my invention.

Fig. 2 is an edge view thereof.

Fig. 3 is a section on the line 3—3 of Fig. 1.

Referring to the drawing, 10 designates the body of the file, which may be of any suitable character, as for instance, flat bastards, mill bastards, square files, rat tail files, wood rasps, etc.

The shank 11 is flat and integral with the body of the file and is of the same thickness as the body of the file. This shank is extended laterally and rearwardly, as shown in Figure 1, and is disposed in the same plane as the toothed portion or body of the file. Welded to the extremity of the shank 11 is a looped portion 12, which is returned upon itself and welded at its forward end at 13 to the body of the file. This portion 12 has a thickness approximately the same as the

shank and the body of the file. The shank 11 and the section 12, together form a handle loop, and this handle loop, lying as it does in the same plane as the body of the file and having a thickness approximately the same as the body 5 of the file, does not interfere in any way with the free movement of the file when the file is used.

My invention provides every file with a handle so that it will save the necessity of using wood handles or the patented detachable handles, and 10 when the file is not in use, it can be hung up on a nail.

By having an integral handle on the file it will eliminate the possibility of the handle breaking while filing is being done, with the likelihood 15 of the shank of the file piercing the operator's hand.

I claim:

A file having a flat toothed body and a flat 20 integral shank extending laterally and rearwardly from the butt end of the file, the shank having a thickness approximately equal to that of the file and being disposed in the same plane as the toothed portion of the file, and a section welded 25 to one end of the extremity of the shank and at its other end being welded to the body of the file, the shank and welded section together forming a handle loop, the welded portion having a thickness approximately the same as the shank 30 and body of the file.

PIERCE J. MURPHY.
